UNITED STATES PATENT OFFICE

GUSTAF DAVID SUNDSTRAND, DECEASED, LATE OF ROCKFORD, ILLINOIS, BY PEARL SUNDSTRAND, EXECUTRIX, OF ROCKFORD, ILLINOIS, AND JOHN F. BENNER, OF ROCKFORD, ILLINOIS, ASSIGNORS TO SUNDSTRAND MACHINE TOOL CO., OF ROCKFORD, ILLINOIS, A CORPORATION OF ILLINOIS

LATHE

Application filed September 13, 1930. Serial No. 481,684.

The invention relates to lathes and more particularly to automatic lathes adapted to perform a plurality of operations.

The general object of the present invention is to provide an automatic lathe of a universal character as distinguished from special single purpose machines, adapted to operate with a speed and accuracy equal to such single purpose machines and capable of convenient and rapid set up for any one of a large variety of automatic cycles.

Another object is to provide a lathe having improved and simplified cam actuating mechanism for the movable supports arranged for convenient and accurate adjustment whereby to vary the relative timing of the working strokes of the supports.

Another object is to provide a lathe embodying a novel mechanism for relieving the front tools at the beginning of the carriage return stroke.

Another object is to provide such a lathe embodying a new and advantageous control mechanism.

Another object is to provide a lathe embodying a control mechanism having an improved safety stop device whereby the lathe operation may be stopped by a rapid and easily accomplished movement of a conveniently positioned control lever.

Other objects and advantages will become apparent from the following description taken in connection with the accompanying drawings in which:

Fig. 1 is a front elevational view, partially in section, of a lathe embodying the invention in its preferred form.

Fig. 2 is an elevational view of the headstock end of the machine shown in Fig. 1.

Fig. 3 is an elevational view of the tailstock end of the machine, the tailstock being shown in dotted outline.

Fig. 4 is a plan section showing the headstock gearing, the section being taken along the line 4-4 of Figs. 2 and 3.

Fig. 5 is a fragmental plan section taken along the line 5-5 of Fig. 2 and showing a part of the headstock gearing.

Fig. 6 is a fragmental plan section taken along the line 6-6 of Fig. 3 and showing another part of the headstock gearing.

Fig. 7 is a plan section taken along the line 7-7 of Figs. 11 and 12 and showing a part of both the feed and traverse gearing for the tool supports.

Figs. 8 and 9 are fragmental plan sections taken along the lines 8-8 and 9-9 respectively of Fig. 12.

For purposes of disclosure the preferred 30 form of the invention is illustrated in the drawings and will hereinafter be described in detail as applied to a particular form of lathe, but it is to be understood that this disclosure is not intended as a limitation of the 35 invention to this type of machine tool, it being contemplated that various changes might be made by those skilled in the art to adapt the invention to other types of tools without departing from the spirit and scope of the 40 invention as defined by the appended claims.

In the preferred form chosen for disclosure herein, the invention is illustrated as embodied in a lathe having a bed 10 with an upstanding headstock 11 at one end thereof. 45 Between the headstock 11 and the other end of the bed a plurality of longitudinally extending ways 12 and 13 are provided and upon the forward pair of ways 12 a front carriage 14 is slidably mounted. The front carriage 14 has a cross slide 15 mounted thereon 50 for movement transversely of the lathe. Upon the rear pair of ways 13, a rear carriage 16 is mounted for adjustment longitudinally of the lathe and carries a transversely mov- 55 able cross slide 17, arranged to move at an angle to the horizontal. In the headstock 11 a work spindle 18 is rotatably supported in longitudinally spaced bearings. A rotatable tailstock spindle 19 is mounted in alignment 60 with the headstock spindle in a frame 20 which is longitudinally adjustable upon the two adjacent ways 12 and 13 and the spindle 19 may be longitudinally adjusted in the frame 20 by conventional means including 65 a hand wheel 21.

Headstock gearing

The present invention provides for actuating the headstock spindle 18 at either one of two different speeds from a driving motor 22 mounted in the rear portion of the base beneath the headstock. The headstock gearing is best illustrated in Figs. 4 to 6 and 13 and comprises a main shaft 23 mounted in the headstock 11 parallel to the spindle 18 and having a pulley 24 thereon which may be connected by means of a belt 25, (Fig. 2) to a pulley 26 (Fig. 2) fixed on the motor shaft. 75

From the main shaft 23, two differently speeded geared connections are provided to the headstock spindle 18, the two gear trains being adapted to be selectively connected to the spindle and each train preferably embodying a pair of conveniently positioned pick-off gears for varying the relation of the two spindle speeds. As illustrated herein the high speed gear train includes a gear 30 loosely mounted on the shaft 23 and arranged to drive a shaft 31 (Fig. 5) through the medium of intermediate gears 32 and 33. The shaft 31 is also mounted parallel to the spindle 18 and projects through the left hand end of the headstock 11 to receive a pick-off gear 34 (Figs. 2 and 5) which is arranged to mesh with a complementary pick-off gear 35 (Figs. 2 and 4) secured on the end of a parallel shaft 36. The shaft 36 which extends entirely through the headstock 11 and is common to both the high speed and low speed gear trains, carries a gear 37 which meshes with a gear 38 fixed on the headstock 100 spindle 18. 95

The low speed gearing from the main shaft 23 to the headstock spindle 18 includes a gear 40 loosely mounted on the shaft 23 in spaced relation to the gear 30 and arranged to drive a shaft 41 (Fig. 6) through the medium of intermeshing gears 42 and 43. The shaft 41 projects through the right hand end of the headstock 11 in spaced relation to the end of the shaft 36 and carries a pick-off gear 44 arranged to mesh with a complementary pick-off gear 45 secured on the projecting end of the shaft 36. Between the two gears 30 and 40, a clutch member 46 is splined on the shaft 23 and at its opposite ends has a pair of friction clutches 47 and 48 for engaging selectively either the high speed or low speed gear train. 110

Feed shaft actuating mechanism

The front carriage and cross slide and the rear cross slide are arranged to be actuated at feed speeds from the spindle 18 and at traverse speeds directly from the motor 22. 12 The feed and traverse gearing is best illustrated in Figs. 7 to 12 and 14. The feed and traverse drives include a common feed shaft 54 extending transversely of the bed 10 beneath the headstock which is driven at feed 13

speeds from the spindle and at traverse speed directly from the motor 22.

The traverse drive to the feed shaft 54 includes a shaft 55 (Figs. 7 and 14) mounted 5 in the base so as to extend longitudinally thereof and connected to the shaft of the motor 22 by sprockets 56 and 57 and a chain 58 (Fig. 14). On the shaft 55 within a gear box 59 is a gear 60. The gear 60 engages and 10 drives a gear 61 on a parallel shaft 62 which extends through the wall of the gear box 59 and carries a worm 63 arranged to engage a worm wheel 64 (Figs. 11 to 14) loosely mounted on the feed shaft 54. To cause rotation of the feed shaft 54 at the traverse speed in a forward direction the worm wheel 64 may be clutched to the shaft by a traverse clutch element 65 having teeth 66 on one end thereof for engaging clutch teeth on the 15 worm wheel 64. At its other end the traverse clutch 56 has teeth 67 for engaging corresponding teeth on another loosely mounted worm wheel 68 which is driven in a reverse direction by a worm 69 (Figs. 7 and 14) fixed 20 on a shaft 70 mounted in the bed 10 beneath the feed shaft 54.

The shaft 70 projects into the gear box 59 and carries a gear 71 meshing with a gear 72 fixed on the shaft 62 so that the shafts 62 30 and 70 are driven in reverse directions. The traverse clutch 65 has a neutral position so that the feed shaft 54 may be actuated independently of the traverse drive.

The feed drive for the feed shaft 54 is 25 taken from the spindle 18 through a sprocket 75 (Figs. 1 and 14) fixed on the spindle 18 and engaging a chain 76 mounted within a casing 77 on the headstock end of the base. At its lower end the chain 76 engages a 30 sprocket 78 mounted on a horizontal shaft which also carries a second sprocket 79. An endless chain 81 engages the sprocket 79 and drives a sprocket 82 (Figs. 1 and 7) carried on the projecting end of a horizontal shaft 45 83 journaled in the bed 10.

Within the bed 10 and outside of the gear box 59, the shaft 83 is coupled at 83^a to a stub shaft 84 projecting into the gear box and carrying a gear 85. A similar stub shaft 86 projecting into and journaled in the gear box 59 carries a gear 87 which is driven from the gear 85 through an intermediate gear 88 mounted within the gear box 59.

At its outer end the stub shaft 86 is coupled 50 at 86^a to a shaft 90, the splined end of which projects through the left end of the bed 10 to receive a pick-off gear 91 (Figs. 7 and 14). A companion pick-off gear 92 on a parallel 55 shaft 93 meshes with the gear 91 and the shaft 93 is coupled at 93^a to a horizontal shaft 94. The shaft 94 carries a worm 95 in driving engagement with a worm wheel 96 (Figs. 11, 14 and 29) which is loosely mounted on the feed shaft 54 and may be connected thereto by means of a splined feed clutch 97.

Thus by selective engagement of the feed clutch 97, the rapid approach clutch 66 or the rapid return clutch 67, the feed shaft 54 may be caused to rotate at feed or traverse speed in a forward direction or at a traverse 70 speed in a reverse direction. It will be seen that the feed speed is capable of a wide range of variation since change gears 34, 35 and 44, 45 are provided in the spindle drives as well as change gears 91, 92 in the feed drive between the spindle and the feed shaft 54. 75

Clutch actuating means

In the present embodiment the feed and traverse clutches as well as the spindle speed-change clutch 46 are hydraulically actuated. As illustrated herein the clutches are shifted to engaged positions by means of pressure fluid operated piston and cylinder devices, against the action of springs which tend normally to maintain the clutches in their disengaged positions. As shown in Fig. 29, the feed and traverse clutch actuating means comprises a tubular member 100 which is supported adjacent and parallel to the feed shaft 54 and has a plurality of transverse walls 101 forming cylinders 102 and 103 in which pistons 104 and 105 are slidably mounted. The pistons 104 and 105 have laterally projecting arms 106 and 107 projecting through the walls of the cylinders, the arm 106 engaging the feed clutch 97 while the arm 107 engages the traverse clutch member 65. 80 85 90 95

An expansive spring 108 in the cylinder 102 urges the piston 104 to a position in which the feed clutch 97 is disengaged, and to engage the clutch, pressure fluid is admitted to the other end of the cylinder 102 through a port 109. Within the piston 105 a spring 110 is mounted so as to be engaged at opposite ends by the enlarged heads of a pair of pins 111. The pins 111 extend through plugs 112 in the ends of the piston 105 and engage the end walls 101 of the cylinder so that the piston 105 is normally urged to a central position in the cylinder, in which position the traverse clutches are disengaged. To engage the clutch 66 to cause rapid approach movement of the feed shaft 54, pressure fluid is admitted to one end of the cylinder through a port 114, while the rapid return clutch 67 may be engaged by admitting pressure fluid to the other end of the cylinder through a port 113. 100 105 110 115 120

A similar piston and cylinder device is provided for actuating the spindle speed change clutch 46. As shown in Figs. 4 and 29, this device consists of a cylinder 120 having a piston 121 slidably mounted therein. The piston 121 has an arm 122 projecting through a slot in the cylinder and engaging the clutch 46, so as to form a shifting yoke therefor. Within the piston 121 a spring device 123 is mounted, similar to that embodied in the pis- 125 130

ton 105 above described, and arranged normally to hold the clutch 46 in its neutral position. To shift the clutch 46 in one direction or the other, pressure fluid connections may be provided to the opposite ends of the cylinder 120 as hereinafter more fully described.

Rear cross slide actuating mechanism

As hereinbefore mentioned, the feed shaft 54 is arranged to actuate the front carriage 14 as well as the front and rear cross slides 15 and 17. Such actuation is preferably obtained by means of a plurality of somewhat similar cam devices driven from the feed shaft 54, one cam being provided for actuating each cross slide and a third cam being provided for longitudinally reciprocating the front carriage 14. As illustrated herein, the cams are in the form of cylinders or drums 130, 131, 132 (Figs. 11, 12 and 16) mounted in the bed 10 adjacent to the left end thereof for rotation about longitudinally extending horizontal axes. Preferably each cam drum is adjustably connected to the feed shaft 54 to permit variation of the timing of the working strokes of the various tool supports and is also adjustably connected to its particular support so as to permit of adjustment of the position of the working stroke with relation to the bed.

The mounting of the rear cross slide cam 130 is shown in detail in Fig. 16 and comprises a pair of axially aligned sleeves 133 and 134 surrounding a shaft 135, the sleeves being rotatably supported in bearings 136 in the bed 10 in such a manner that the left hand end of the shaft 135 and the sleeve 133 project outside of the bed. The cam 130, which is tubular in form and is held in fixed longitudinal position in the bed, surrounds and is slidably keyed to the sleeve 133. Rotation is imparted to the cam drum 130 through the sleeve 134 and to this end a plurality of interengageable teeth 137 (Fig. 16) are provided on the adjacent ends of the sleeves 133 and 134. The teeth 137 are maintained in operative engagement by the shaft 135, a collar 138 on the right end thereof and a nut 139 threaded on the projecting left end of the shaft. Thus by loosening the nut 139 the sleeve 133 may be moved outwardly of the bed to disengage the clutch teeth 137 on the sleeves 133 and 134 so that the sleeve 133 and the cam 130 may be rotated freely for purposes of angular adjustment. To facilitate such adjustment, the projecting left end of the sleeve 133 is squared as at 140 (Fig. 15).

As shown in Figs. 11, 12 and 14, the rear cam 130 is driven from the feed shaft 54 by means including a pair of change gears 141 and 142, the gear 141 being secured on the splined forward end of the feed shaft 54 while the gear 142 is secured on a parallel shaft 143 extending toward the rear of the

bed. At its rear end the shaft 143 carries a gear 144 which, through gears 145 and 146 drives a horizontal shaft 147. Upon the shaft 147 a worm 148 is carried which engages a worm wheel 149 splined to the sleeve 134. Thus when the worm wheel 149 is rotated, such rotation will be transmitted through the sleeve 134 and the clutch teeth 137 to the sleeve 133 which through its splined connection will cause rotation of the cam 130. If desired the shaft 147 may be provided with a gear 150 for driving suitable attachments which may be mounted upon the lathe.

For the purpose of transmitting movement from the cam 130 to the rear cross slide 17 the cam has a spiral groove 151 formed therein with dwell portions 151^a at each end thereof. A follower 152 engages the cam groove 151 and is carried by a slide 153 of rectangular cross section mounted in the bed for movement parallel to the axis of the cam drum. Extending longitudinally through the slide 153 is a connecting rod or shaft 154 rotatably mounted in the slide and fixed against longitudinal displacement relatively thereto. The connecting rod 154 extends longitudinally of the bed and is screw threaded into a slide 155 mounted in the lower portion of the rear carriage 16 for longitudinal reciprocation therein. By rotation of the shaft 154 the connection between the cam drum 130 and the slide 155 may be adjusted and to facilitate such adjustment the end 156 of the connecting rod 154 projects beyond the left end of the slide 153 and is squared as shown in Figs. 15 and 17.

When the slide 155 is reciprocated a corresponding reciprocation of the rear cross slide 17 is obtained by means shown in Figs. 18 and 20. This means comprises a bell crank formed by a shaft 160 mounted in the carriage 16 for rotation about an axis perpendicular to the plane of movement of the cross slide and carrying arms 161 and 162 at the upper and lower ends thereof respectively, the upper arm 161 carrying a pin 163 engaging in a transverse slot 164 formed in the cross slide 17. At its outer end the lower arm 162 carries a downwardly projecting pin 165 which may engage a transverse cam slot 166 formed in the slide 155 (Fig. 20). The arrangement of the bell crank is such that, when the slide 155 is moved toward the tailstock end of the machine (that is upwardly as shown in Fig. 20), the cross slide will be moved toward the work and after a given range of movement in this direction the pin 165 moves out of the slot 166 and engages a cam surface 168 on the side of the slide 155 so that during continued movement of the slide in the same direction the cross slide will be held stationary in its innermost position. In order that the pin 165 may be directed into the transverse slot 166

upon return movement of the slide 155, a hook shaped member 169 projects rearwardly from the slide 155 at the left or far edge of the slot 166.

5 Front carriage actuating mechanism

As hereinbefore pointed out, the front carriage cam 131 is preferably of the same form, has the same adjustable features and is mounted in the same manner as the cam 130, the position of the cam 131 being indicated in Figs. 2 and 11. A slide 175 similar to the slide 153 is mounted above the cam drum 131 (Fig. 11) and carries a roller 176 engaging the cam, the slide 175 being provided with a connecting rod 177 with one end rotatably secured in the slide in a manner similar to the mounting of the connecting rod 154. At its other end the connecting rod 177 is screw threaded into a member 178 (Figs. 21 and 22), mounted in the front carriage 14 on a supporting plate 179 and between a pair of end plates 180 and 181. Thus upon rotation of cam 131 the connecting rod 177 will cause the member 178, through its abutment with one of the end plates 180 or 181, to move the front carriage 14 longitudinally of the bed.

The cam 131 is driven from the feed shaft 54 through a gear 182 on the feed shaft, an intermediate gear 183 (Figs. 8, 12 and 14), engaging a gear 184 fixed on a horizontal shaft 185, and a worm 186 on shaft 185 engaging a worm wheel 187 fixed on the end of the cam 131. The other end of the shaft 185 projects from the front of the bed 10 and carries a handwheel 188 through which the feed shaft 54 may be manually actuated when the feed and traverse clutches are disengaged.

Front cross slide actuating mechanism

The cam 132 for actuating the front cross slide 15 is mounted in the bed 10 parallel and adjacent to the cam 131 (Figs. 2, 11 and 14) and a pair of interengaging gears 190 and 191 carried by the two cams cause the cam 132 to be driven simultaneously with the cam 131. A slide 195 mounted above the cam 132 (Fig. 11) carries a follower 196 arranged to engage the cam. A connecting rod 197 similar to the connecting rod 154 extends from the slide 195 and is screw threaded into a slide 198 (Figs. 21 to 24). The slide 198 is mounted in the lower portion of the front carriage 14 adjacent to the bar 178 and above the supporting plate 179 and is arranged to slide longitudinally through the end plates 180 and 181. The longitudinal reciprocation of the slide 198 causes transverse reciprocation of the front cross slide 15 through a bell crank device similar to that used in the rear cross slide actuating mechanism as shown in Figs. 21 to 24. This device 85 comprises a vertical shaft 200 mounted in

the carriage 14 and carrying arms 201 and 202 at its upper and lower ends respectively. The upper arm 201 is engaged with the cross slide 15 by a pin and slot connection so that upon oscillation of the shaft 200 the cross slide will be actuated. At the outer end of the lower arm 202 a boss 203 projects downwardly and carries a pin 204 (Fig. 21), adapted to engage a transverse slot 205 (Fig. 23) formed in the upper side of the slide 198. 70 75

Thus when the pin 204 is engaged with the slot 205 and the slide 198 is moved to the right as shown in Fig. 23, the arm 202 will be moved in a counter-clockwise direction so as to advance the cross slide 15. As such movement of the slide continues the pin 204 will move out of the slot 205 and the boss 203 will engage and slide along a cam surface 206 (Figs. 21 and 23) on the slide 198 so that the cross slide will remain stationary. In order 80 85 to direct the pin 204 into the transverse slot 205 upon return movement of the slide 198, a hook-like projecting member 207 is mounted on the slide 198 as shown in Fig. 32.

As herein shown, the lathe embodies means 90 for withdrawing the front tools at the beginning of the carriage return stroke so that they do not mar the finished work piece and this means is preferably connected to and operated by the front carriage actuating means 95 and acts through the cross slide actuating mechanism to obtain the desired movement of the front cross slide. To this end the member 178 has a slight lost motion with respect to the carriage 14 during which it is ineffective 100 to move the carriage and is arranged during such movement to cause the cross slide 15 to be actuated in accordance with the direction of movement of the member 178. 105

The member 178 (Figs. 21 and 22) has an angularly extending vertical surface 210 formed along the lower edge thereof engaging a complementary surface 211 formed on the carriage 14 so that during the non-carriage propelling movement of the member 178 110 from the position shown in Fig. 22 into abutment with the plate 181, the member 178 will be moved to the right, that is toward the front of the lathe. It will be noted in Fig. 21 that the forward surface of the member 178 engages the rear side of the boss 203, the other side of which engages the cam surface 206 of the slide 198, and in order to permit transverse movement of the member 178, 115 the slide 198 is held in position by means which may be released when such transverse movement is desired. 120

As illustrated in Fig. 22, this means comprises a wedge 212, mounted on the forward side of the slide 198 for limited sliding movement longitudinally of the slide 198 and arranged to act against a rearwardly facing angular surface 213 formed in the carriage 14. Thus, as shown in Fig. 22, when the wedge 212 is moved toward the tailstock end 125 130

of the machine (upwardly in Fig. 22) the slide 198 will be held against transverse displacement. For the purpose of moving the wedge 212 to its inoperative position when the relieving action is desired, a lever 214 is positioned in a recess in the bottom plate 179 and is pivoted at its mid point to the plate. At its opposite ends the lever 214 has upstanding pins 215, one of which projects into a suitable recess in the bottom of the member 178, while the other pin 215 projects into a transverse slot 216 in the bottom of the wedge 212. Thus, when the member 178 is moved toward the tailstock end of the machine the lever 214 will retract the wedge 212 so as to permit transverse displacement of the slide 198, and the engagement of the angular surfaces 210 and 211 will cause the member 178 to move the boss 203 forwardly of the machine. This causes a slight clockwise movement of the shaft 200 (Fig. 23) and therefore withdraws the tools a slight distance away from the work.

When the member 178 is moved in the opposite direction, the lever 214 moves the wedge 212 back to its operative position (Fig. 22) so that the normal operative relation between the slide 198 and the cross slide actuating arm 202 is established.

30 *Hydraulic circuits and manual control*

As hereinbefore described, the various control clutches of the present machine are provided with piston and cylinder devices for actuating the clutches and a unitary control valve is preferably provided for all of the piston and cylinder devices. As herein shown a tubular valve casing 220 (Figs. 25, 26, 27 and 29) is mounted on the bed 10 within a frame 221 which is positioned in front of the headstock 11. The valve casing 220, in the present case, extends transversely of the machine and has a valve member 222 slidably mounted therein. Within the bed 10, an oil pump 223 is mounted, arranged to be driven from the motor 22 whenever the motor is in operation by suitable means (not shown) and operable to pump fluid under pressure from a supply tank 224 through a supply conduit 224^a to the valve casing 220. From the valve casing 220 the pressure fluid is distributed to the various piston and cylinder devices in accordance with the longitudinal position of the valve member 222 within the casing.

In Fig. 29, an exemplary hydraulic circuit is illustrated, this circuit being designed for work on which two different spindle speeds may be used as the operation progresses. In such an operation the spindle may remain stationary during the rapid approach movement of the supports and as soon as the feeding movement of the supports has started the spindle may be rotated at comparatively slow speed. While being rotated at such a slow

speed the larger diameter cuts may be made and when these cuts have been completed, the spindle speed may be increased. As soon as the cutting operation has been completed the spindle is preferably stopped and the supports retracted at rapid traverse speed.

The valve 220 is designed for such a working cycle and has five longitudinally spaced positions, arranged in the following order from front to rear: (1) rapid approach, hereinafter designated as R. A., (2) spindle and feed at low speed, hereinafter designated as F¹, (3) spindle and feed at high speed, hereinafter designated as F², (4) neutral, designated as N, and (5) rapid return, hereinafter designated as R. R. The pressure fluid supplied to the valve casing is conducted through a bore 225 in the valve member 222 to a plurality of radially extending ports 226 from which the fluid is conducted to the various piston and cylinder devices in accordance with the position of the valve.

When the valve 222 is in its rapid approach position, the ports 226 register with an annular groove 227^a (Fig. 29) and the fluid is conducted from the groove 227^a through a conduit 228 which is connected to the port 114 of the cylinder 103 so as to engage the rapid approach clutch 66.

When the valve 222 is moved rearwardly to its next or F¹ position, the valve ports 226 register with another annular groove 227^b which is connected to one end of the cylinder 120 by a conduit 230 so as to engage the low speed spindle clutch 48. The pressure fluid from the groove 227^b also engages the feed clutch 97, preferably after the spindle has started to rotate. To this end a conduit 231, extending from the port 109 of the feed clutch cylinder 102, is connected to the side of the cylinder 120 at 232 so that the fluid from the cylinder is not admitted to the conduit 231 until the spindle clutch 48 is engaged. By this arrangement the feed clutch operation is timed with respect to the spindle clutch, so that the feed clutch is disengaged before the disengagement of the spindle clutch whereby to cause the cut to be cleared.

In the F² position of the valve 222, the ports 226 communicate with an annular groove 227^c which is connected with the other end of the cylinder 120 by a conduit 233 so as to cause engagement of the high speed spindle clutch 47. For the purpose of engaging the feed clutch when the valve is in its F² position a conduit 234, extending from the port 109 of the feed clutch cylinder 102, is connected at 235 to the side of the cylinder 120 in the same manner as the conduit 231 so as to provide for the same interlocked actuation of the spindle and feed clutches.

When the valve 222 is in its neutral position, the ports 226 register with another annular groove 227^d from which the pressure fluid

is by-passed to the supply tank 224 through a pipe 236.

In the rapid return position of the valve an annular groove 227^e registers with the ports 226 and the pressure fluid passes from the groove 227^e through a conduit 237 which is connected to the port 113 of the cylinder 103 so as to engage the rapid return clutch 67.

The present embodiment of the invention provides for either manual or automatic operation. For the purpose of manually actuating the valve member 222, a rack 240 is formed on the underside of a slide bar 239 (Figs. 25 and 29) mounted in the frame 221 coaxially with and connected to the valve 222. A shaft 241 (Fig. 25) extending transversely from the valve member has a pinion 242 at one end thereof engaging the rack 240. The shaft 241 is rotatably journaled in the frame member 221 and has a beveled gear 243 (Fig. 26) at the other end thereof engaged by a beveled gear 244 (Fig. 28) which is connected to the handle 245 mounted in an angular position on the outside of the frame member 221. Thus, by moving the handle 245 about its pivotal axis, the valve member 222 may be shifted from one position to another.

Automatic control means

Means is provided for automatically controlling the operation of the lathe and this means preferably embodies a rotary member designated generally as 246 (Figs. 1, 2, 3, 25, 26 and 29) which is mounted on a transverse shaft 247, rotatably journaled in the frame 221. The shaft 247 is driven in forward and reverse directions in timed relation to the feed shaft 54 by means of a gear 248 secured on the shaft 185 (Fig. 14) which drives the control shaft through gear 249, shaft 250, and gears 251 and 252 (Figs. 9 and 14).

In the present embodiment of the automatic control means, the valve member 222 is constantly urged rearwardly in the valve casting by a spring 254 (Figs. 25 and 26) and is restrained against such movement by means including the control member 246. To this end the control member 246 is preferably of drum-like form, stepped as shown in Figs. 25 and 29 to form a plurality of annular portions or surfaces 255^a, 255^b, 255^c and 255^e, of different diameters and also to provide a plurality of forwardly facing annular surfaces or abutments 256^a, 256^b, 256^c and 256^e. For engagement with any one of the abutments 256, a detent 257 is mounted in the forward end of the horizontal bar 239 for sliding movement transversely of the bar 239 and radially with respect to the stepped control drum 246 (Figs. 25 and 26). As hereinbefore mentioned, the bar 239 is mounted in the frame 221 in alinement with the valve member 222 and is connected to the valve so

that the position of the valve is determined by the longitudinal position of the bar 239. Upon the lower end of the detent 257 is a head 259 having a side surface 260 adapted to abut any one of the vertically positioned annular abutments 256 of the control drum. The head 259 also has an end surface 261 adapted to ride upon any one of the peripheral surfaces 255. By this arrangement the surface 256 with which the detent is engaged by the action of the spring 254 is determined by the vertical position of the detent.

Thus when the valve 222 is moved by means of the manual control handle 245 and the detent 257 is positioned over the surface 255^a, the detent 257 will drop downwardly until the surface 267 thereof engages the annular surface 255^a. The valve 222 will then be in its rapid approach position and will be maintained in this position by the engagement of the surface 260 of the detent with the abutment 256^a also designated as R. A. in Figs. 25 and 29. As soon as the valve 222 is moved to its rapid approach position, as above described, the feed shaft 54 will start to rotate and will cause a corresponding rotation of the control drum 246 in the direction indicated by the arrow in Fig. 26.

In order to lift the detent 257 automatically at the proper time, an L-shaped trip dog 262 is secured on the control drum 246 by means of a bolt extending through one leg of the trip dog and engaging an annular T-slot 263 formed in the forward end of the control drum. The other leg of the trip dog 262 extends rearwardly across the surface 255^a as shown in Fig. 25 and is beveled as shown in Fig. 26 to provide a sloping cam surface 264 which gradually raises the detent 257 as the drum rotates. When the detent has been raised to the level of the surface 255^b, it is drawn rearwardly by the spring 254 until the surface 260 engages the abutment 256^b (also designated as F1) on the control drum. When the plunger is in this position the valve 222 is in its low speed position so that the spindle is rotated at its low speed and the tool supports are advanced at a corresponding feed speed.

A similar trip dog 265 is provided on the control drum 246 overlying the surface 255^b and serves to lift the detent 257 over the next step of the drum so that it may engage the annular abutment 256^c, also designated as F² in Figs. 25 and 29. The valve 222 is then in its third position in which the high speed spindle drive is effective and the tool supports are advanced at a corresponding feed speed.

Upon the completion of the cutting operation, a reverse dog 267, positioned on the control drum so as to overlie the surface 255^c (Fig. 25) raises the detent 257 so that it may be drawn rearwardly into engagement with the abutment 256^e, also designated as RR in

- Figs. 25 and 29. When the detent 257 is in this position, the valve 222 is in its rear position and causes a rapid return movement of the tool supports with a corresponding reverse rotation of the control drum 246. When the tool supports have reached their initial positions, a stop dog 268 secured on the control drum 246 moves the detent forwardly until the valve 222 is in its neutral position.
- 10 As herein shown the trip dog 268 is bolted to a T-slot 269 in the rear surface of the drum 246 and projects forwardly over the edge of the drum so as to engage the head 259 of the detent.

15 *Safety stop device*

The lathe preferably embodies means whereby the control valve 222 may at any time be moved quickly and with certainty 20 from any of its operative positions directly to and not beyond, its neutral position, so as to stop the operation of the lathe. This means acts as a safety stop and enables the operator, in case of an emergency, to stop the machine 25 by a simple and easily performed movement. In the present case, the safety stop means includes a manually shiftable lever 275 having valve actuating means associated therewith whereby a unidirectional movement of the 30 lever 275 as far as it is permitted to go in that direction will move the control valve to and not beyond its neutral position from any of its other positions even though there are other operative positions beyond the neutral position. As herein shown in Figs. 25 and 26, the 35 lever 275 is fixed on the projecting end of a horizontal shaft 276 which is rotatably mounted in a pair of spaced upwardly projecting brackets 277. Between the two brackets 40, an arm 278 is fixed on the shaft 276 so as to project forwardly therefrom for connection with the detent 257. To provide such a connection the forward end of the arm 278 is bifurcated as at 279 so as to embrace the opposite sides of a transversely extending bar 45 280 secured on the detent 257. In the opposite sides of the bar 280 horizontal grooves 281 are formed and these grooves are slidably engaged by blocks 282 pivotally secured on the 50 bifurcated ends of the arm 278.

Thus by moving the lever 275 rearwardly the detent 257 may be raised out of engagement with the drum 246 and means is provided which cooperates with the detent 257 in 55 its upward movement to cause it to be moved parallel to the axis of the valve 222 until the valve is in its neutral position. This means as herein shown comprises a member 285 supported by the brackets 277 and having a 60 downwardly opening conical recess 286 adapted to cooperate with the conical upper end 287 of the detent 257 to stop the movement of the detent at the proper point. Thus if the valve is in its rapid approach or one of 65 its feed positions, the detent 257 will be moved

upwardly so that the conical end 287 engages the forward sloping surface of the recess 286, the spring 254 acting to draw the detent toward the neutral position of the valve as the head 259 of the detent is raised out of engagement with the annular abutments, while if the valve is in its rapid return position, the detent will be moved upwardly to engage the rear surface of the recess 286. In either case the continued upward movement of the detent by 70 means of the lever 275 will cause the detent to be moved in a horizontal direction so as to bring the valve 222 to its neutral position.

The safety stop lever 275 is also adapted for 75 use in shifting the valve 222 to its rapid approach position to initiate the automatic cycle of support movement. For this purpose, as shown in Figs. 25, 26 and 29, a toggle device is employed. The toggle device shown consists of a pair of links 290, one of which is loosely pivoted on the shaft 241 while one end of the other link is pivoted at 291 on the outer end of the slide 239. The other ends of the two links 290 are pivoted together by means of a bolt or stud 292 which projects laterally from the links and under the arm 278 of the lever 275. For cooperation with the projecting end of the bolt 292, a cam surface 293 is formed on the lower side of the arm 278 so that when the lever 275 is moved forwardly, the bolt 292 will be engaged so as to extend the toggle links 290 and move the valve 222 to its forward or rapid approach position. A lug 294 on the arm 278 serves to engage the frame 221 and limit such movement of the valve 222.

We claim as our invention:

1. A lathe having, in combination, a bed, movable tool supports on said bed, a rotatable headstock spindle, a prime mover, two differently speeded driving connections from said prime mover to said spindle including a common clutch element, a pressure fluid actuated piston and cylinder device for shifting said clutch element, a feed shaft rotatably mounted in said bed and operatively connected to said supports, a constant speed reversible traverse drive directly from said prime mover to said feed shaft and including a reversing clutch, a pressure fluid actuated piston and cylinder device for selectively engaging said clutch to obtain forward or reverse rotation of said feed shaft, a driving connection from said spindle to said feed shaft for rotating said shaft at a feed speed determined by the speed of said spindle and including a feed clutch, a pressure fluid actuated piston and cylinder device for controlling said feed clutch, valve means for controlling the operation of said piston and cylinder devices, and means driven in unison with said feed shaft for controlling the position of said valve means.

2. A lathe comprising, in combination, a bed, a headstock spindle rotatably mounted thereon, movable tool supports mounted on

- the bed, a prime mover, a high speed drive and a low speed drive from said prime mover to said spindle, each of said drives including a pair of alterable change gears and a clutch, 5 pressure fluid actuated means for selectively engaging said clutches, a feed shaft operatively connected to said supports, a reversible traverse driving connection between said prime mover and said feed shaft including 10 a traverse reversing clutch, pressure fluid actuated means for engaging said traverse clutch to rotate said feed shaft in forward or reverse directions, a driving connection between said spindle and said feed shaft for 15 rotating said shaft at a feed speed, determined by the speed of the spindle, said feed drive including a pair of alterable change gears and a feed clutch, pressure fluid actuated means for engaging said feed clutch, and 20 valve means for controlling the operation of said pressure fluid actuated means.
3. A lathe comprising, in combination, a bed, a headstock spindle rotatably mounted thereon, movable tool supports mounted on the bed, a prime mover, a high speed drive and a low speed drive from said prime mover to said spindle, each of said drives including a pair of alterable change gears and a clutch, 25 pressure fluid actuated means for selectively engaging said clutches, a feed shaft operatively connected to said supports, a reversible traverse driving connection to said feed shaft including a traverse reversing clutch, pressure fluid actuated means for engaging said 30 traverse clutch to rotate said feed shaft at a feed speed including a feed clutch, pressure fluid actuated means for engaging said feed clutch, valve controlled means for supplying pressure fluid to said spindle clutch engaging means, a conduit for conducting pressure fluid from said spindle clutch engaging means to the feed clutch engaging means.
4. A lathe comprising, in combination, a bed, movable tool supports thereon, a headstock spindle rotatably mounted on the bed, a prime mover, a feed shaft operatively connected to said supports, means deriving 45 power from said prime mover operable to rotate said shaft in forward or reverse directions at a traverse rate, two differently speeded driving connections between said prime mover and said spindle, said connections including a common clutch element shiftable in opposite directions to selectively engage said driving connections, a first pressure fluid actuated piston and cylinder device for shifting said clutch element in either direction, a driving connection between said 50 spindle and said feed shaft including a feed clutch, a second pressure fluid actuated piston and cylinder device operable to engage said feed clutch whereby to cause rotation of said feed shaft at a feeding speed determined by the speed of the spindle, valve controlled means for supplying pressure fluid to said first device, and a pair of conduits extending from the cylinder of said first device to the cylinder of said second device to conduct pressure fluid between the two cylinders, said conduits being connected to the cylinder of said first device so as to delay operation of said second device until said first device has 55 operated.
5. A lathe comprising, in combination; a bed, a headstock spindle rotatably mounted thereon, movable tool supports mounted on the bed, a prime mover, a high speed drive and a low speed drive from said prime mover to said spindle, each of said drives including a pair of alterable change gears and a clutch, pressure fluid actuated means for selectively engaging said clutches, a feed shaft operatively connected to said supports, a driving connection between said spindle and said feed shaft for rotating said shaft at a feed speed including a feed clutch, pressure fluid actuated means for engaging said feed clutch, valve controlled means for supplying pressure fluid to said spindle clutch engaging means, a conduit for conducting pressure fluid from said spindle clutch engaging means to the feed clutch engaging means.
6. A lathe having, in combination, a bed, 100 tool supports movably mounted thereon, a rotatably mounted headstock spindle, a prime mover, a feed shaft operatively connected to said supports, a driving connection between said prime mover and said spindle including a spindle clutch, a first pressure fluid actuated piston and cylinder device for engaging said clutch, a driving connection between said spindle and feed shaft including a feed clutch, a second pressure fluid actuated piston and cylinder device operable to engage said feed clutch, valve controlled means for supplying pressure fluid to said first device and a conduit extending from the cylinder of said first device to the cylinder of said second device and connected to the first cylinder so as to delay operation of said second device until said first device has 105 moved to engage the spindle clutch.
7. A lathe having, in combination, a bed, 110 rotatable work supporting means, a plurality of movable tool supports carried by said bed, a plurality of similar cams mounted for rotation about horizontal axes extending longitudinally of said bed, all of said cams being mounted within the bed adjacent to one end thereof and having spiral cam grooves therein with dwell portions at the ends of the grooves, a plurality of movable members one mounted in said bed adjacent to each of 115 120 125 130

said cams for longitudinal sliding movement parallel to the cams, a follower carried by each member engaging the groove in the adjacent cam, a plurality of connecting rods one extending longitudinally through each of said members and rotatable in said members in fixed longitudinal relation thereto, said rods being adapted at their outer ends for the application of a tool or handle for rotating the rod, and an operative connection between 10 each of said rods and one of said supports, including an element in screw threaded engagement with said rod whereby to permit of adjustment of said connection by rotation 15 of said rod from the outside of said bed.

8. A lathe having, in combination, a bed, rotatable work supporting means, a plurality of movable tool supports carried by said bed, a plurality of similar cam drums mounted for rotation about horizontal axes extending longitudinally of said bed, all of said 20 cams being mounted within the bed and adjacent to one end thereof and having spiral cam grooves therein with dwell portions at 25 the ends of the grooves, a plurality of movable members, one mounted in said bed adjacent to each of said cams for longitudinal sliding movement parallel to the cams, a follower carried by each member engaging the 30 groove in the adjacent cam, a connecting rod extending longitudinally through each of said members and rotatable in said members in fixed longitudinal relation thereto, said rods being adapted at its outer end for the 35 application of a tool or handle for rotating the rod, said rods being operatively connected to said supports by means which may be adjusted by rotation of said rods, and means for driving said cams including an adjustable connection with each of said cams to 40 permit of variation of the angular relation of the cams to each other.

9. A lathe having, in combination, a bed, rotatable work supporting means, a movable 45 tool support mounted on said bed, and means for actuating said support comprising a cam drum having a spiral groove therein and mounted in said bed adjacent one wall thereof for rotation about a horizontal axis perpendicular to said side, a member mounted in 50 said bed adjacent to said cam for sliding movement through said wall of said bed parallel to the axis of said cam, said member having a follower engaging said groove, and 55 means forming an adjustable operative connection between said member and said support, said means including a rod rotatably mounted in said member and projecting to the outside of said bed, said rod being operable 60 upon rotation to adjust said connection.

10. A lathe having, in combination, a bed, rotatable work supporting means, a tool support movably mounted on said bed, and means for actuating said support comprising 65 a tubular cam drum having a spiral groove

therein and supported in fixed longitudinal position in said bed adjacent to one wall thereof, means including a cam follower forming an operative connection between said cam and said support, a driving member rotatably supported in said bed coaxially with said drum, a sleeve extending from the outside of said bed into said tubular cam drum and keyed to said drum so as to permit of longitudinal movement of the sleeve, said driving member and said sleeve having teeth formed thereon engageable by longitudinal movement of said sleeve, and means acting between said driving member and said sleeve operable to hold said teeth in engaged relation, said means being releasable exteriorly of said bed so as to permit of angular adjustment of said cam and said driving member.

11. A lathe having, in combination, a bed, rotatable work supporting means, a movable tool support on said bed, and actuating means for said tool support comprising, a movable cam mounted in said bed, a member mounted for sliding movement through a wall of said bed, a follower fixed on said member and engaging said cam, and means forming an adjustable operating connection between said member and said tool support, said means including a rod rotatably mounted in said member in fixed longitudinal relation thereto and projecting through said member to the outside of said bed, said rod being operable upon rotation to adjust said connection.

12. A machine tool comprising, in combination, a bed, a movable support thereon, 100 actuating means for said support, controlling means for said actuating means including a movable member having a plurality of operative positions arranged so that when said member is moved step by step from one 105 extreme position to the other the support will be moved through a cycle consisting of rapid approach, feed, and rapid return movements, said member having a neutral position located between its feed and rapid return positions, resilient means urging said member toward its rapid return position, a detent carried by and movable transversely with respect to said member, a control drum arranged to be moved in timed relation to said 110 actuating means, said drum being of step-like form to provide a plurality of surfaces adapted for engagement by said detent to determine the operative position of said member, a plurality of trip dogs on said drum 115 each operable to disengage said detent from one of said surfaces, so that said detent may be moved by said resilient means into engagement with another of said surfaces, and a cam device on said drum operable to engage said detent during rapid return movement of the support to move said member to its neutral position.

13. In a machine tool having a bed, a movable support thereon, actuating mechanism 130

- for said support, and controlling means for said actuating mechanism including a member having a plurality of operative positions in which said mechanism is effective to move 5 said support and also having another position in which said mechanism is ineffective, a detent connected to and movable transversely of said member, a rotatable drum driven in timed relation to said actuating mechanism, 10 said drum being of step-like form to provide a plurality of surfaces adapted for selective engagement by said detent to determine the position of said member, a control handle operable to shift said member between its 15 various positions, a plurality of trip dogs carried by said drum and operable to shift said detent, and resilient means operable to move said member from one position to another when said detent is shifted. 20 14. A machine tool comprising, in combination, a bed, a support movably mounted thereon, actuating means for moving said support, and controlling means for said actuating mechanism including a movable element having a plurality of positions in which said mechanism is operative to move said support, and also having a position wherein said mechanism is ineffective upon said support, a detent member connected to and movable 25 transversely of said element, a control member mounted on said bed and arranged to move in timed relation to said actuating mechanism, one of said members having surfaces arranged in step-like 30 form adapted for selective engagement with the other of said members to determine the position of said element, means urging said members into abutting relation, and a trip dog on said control member operable, when 35 40 one of said surfaces is effective, to shift said detent member to render another of said surfaces effective to determine the position of said element. 15. A machine tool comprising, in combination, a bed, a movable support on said bed, actuating and controlling means for said support including a shiftable valve and controlling means for said valve comprising a drum rotatably mounted on said bed for movement 45 in timed relation to said actuating means, said drum being of step-like form so as to provide a plurality of outwardly facing peripheral surfaces and a plurality of annular surfaces at right angles to the axis of 50 the drum and to said first mentioned surfaces, a member mounted on said bed for movement parallel to the axis of said drum and operatively connected to said valve, a detent mounted on said member for sliding movement 55 transversely of the axis of said member and radially with respect to said drum, said detent tending normally to move radially inwardly of the drum, the end of said detent being adapted to abut one of the peripheral surfaces of the drum and the side of 60 said detent being adapted to abut one of the annular surfaces of the drum, resilient means urging said member so as to bring said detent into engagement with said annular surfaces, and means on said drum adapted to move said detent radially outwardly of said drum so that said detent 65
- the detent being adapted to abut any one of said annular surfaces, resilient means urging said member so as to bring said detent into engagement with one of said annular surfaces, and trip dogs on said drum adapted to move said detent radially outwardly of said drum so that said detent may be engaged successively with different annular surfaces of the drum. 70 16. A machine tool comprising, in combination, a bed, a support movably mounted on said bed, a rotatable feed shaft operatively connected to said support to move the same, means including a clutch for rotating said shaft at a feed speed, means including a clutch for rotating said shaft at traverse speed, means for shifting said clutches including a member movable to various positions along a given path to determine which clutch is engaged, a detent slideable in said member transversely of said path, means providing a plurality of step-like surfaces some of which are perpendicular to said path and are adapted for engagement by the side of said detent and the others of which are parallel to said path and are adapted to be engaged by the end of said detent, means arranged to press the side of said detent against any one of said perpendicular surfaces, as determined by the parallel surface with which the end of said detent is engaged, and movable means operating in timed relation to said feed shaft and acting to move said detent longitudinally away from the one of said parallel surfaces with which it is engaged whereby to permit said yielding means to shift said member and engage said detent with another one of said perpendicular surfaces. 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

may be engaged successively with different annular surfaces of the drum.

18. In a machine tool having a bed, a support movably mounted thereon, actuating means for said support, and means for controlling said actuating means including a plurality of parallel abutments positioned in stepped relation to each other, a movable detent connected to said controlling means and adapted for engagement with any one of said abutments, means moving in timed relation to said actuating means operable to disengage said detent from the one of said abutments with which it is then engaged, and means connected to said detent and operable when the detent is thus disengaged to move it into engagement with another of said abutments.

19. A machine tool having, in combination, a bed, a movable support thereon, actuating means for said support, and controlling means for said actuating means including a movable member having a plurality of positions, a detent mounted on said member and effective to determine the operative position of said member, and a control device driven in timed relation to said actuating means, said device comprising a drum of step-like form with a plurality of annular surfaces, said detent being arranged to engage selectively certain surfaces of said drum to determine the position of said member, a trip dog on said drum operable to disengage said detent from a first one of said surfaces, and resilient means operable to move said member to a second one of its positions when said detent is disengaged from said first one of said surfaces by said dog, said second position of said member being determined by engagement of said detent with a second one of said surfaces.

20. A lathe comprising, in combination, a bed, rotatable work supporting means, a tool support movably mounted on said bed, means for actuating said support, and means for controlling such actuation including a control member movable between a plurality of positions along a given path, one of said positions being a neutral position, means operable to control the movement of said member from one position to the other whereby to obtain an automatic cyclic movement of said support, and a safety stop device comprising a plunger mounted on said member for longitudinal sliding movement transversely of said path, a lever connected to said plunger and operable by a unidirectional movement to move said plunger longitudinally, and means providing sloping cam surfaces lying in the path of the plunger when it is so moved, and acting on the end of said plunger to move said control member to its neutral position.

21. A lathe comprising, in combination, a bed, rotatable work supporting means, a tool

support movably mounted on said bed, means for actuating said support, and means for controlling such actuation including a reciprocatory control member having a plurality of operative positions, a detent slidable transversely on said control member and effective to determine the operative position of said member, a movable control device adapted to cooperate with one end of the detent to determine the position of said control member whereby to obtain an automatic cycle of movement of said support, and a safety stop device comprising a cam adapted to cooperate with the other end of said detent as it is moved into engagement with the cam to move said control member to its neutral position, and a lever mounted on said bed and connected to said detent, said lever being operable by a unidirectional movement to disengage said detent from said control device and move it into cooperative relation with said cam device so as to bring said control member into its neutral position.

22. In a machine tool having a bed, a movable support thereon, actuating mechanism for said support, and controlling means for said actuating mechanism including a member having a plurality of operative positions in which said mechanism is effective to move said support and also having another position in which said mechanism is inoperative, a detent connected to and movable transversely of said member, a rotatable drum driven in timed relation to said actuating mechanism, said drum being of step-like form to provide a plurality of surfaces adapted for selective engagement by said detent to determine the position of said member, a control handle operable to shift said member between its various positions, a second handle for shifting said member, and means operable by said second handle to stop movement thereof when said member has been moved to its neutral position.

23. A machine tool having in combination, a bed, a support movable thereon, actuating mechanism for said support, and controlling means for said mechanism including a member having a plurality of operating positions in which said mechanism is effective to move said support, said member also having a neutral position in which said mechanism is ineffective to move said support, said neutral position being intermediate two of its other positions, a detent mounted on and movable transversely of said member, a control element moving in timed relation to said actuating mechanism and providing a plurality of abutments adapted for engagement by said detent to determine the position of said member, a control handle for shifting said member to any desired one of its positions and to engage said detent with the corresponding abutment, means including trip dogs on said control element operable to shift said detent

and cause movement of said member from one position to another, a second control handle operable by movement in a given direction to cause said member to be shifted from any one of its operative positions toward its neutral position, and means operable to stop said member when it has reached its neutral position.

24. In a machine tool having a bed, a movable support thereon, actuating mechanism for said support, and controlling means for said actuating mechanism including a member having a plurality of operative positions in which said mechanism is effective to move said support and also having another position in which said mechanism is inoperative, a detent connected to and movable transversely of said member, a rotatable drum driven in timed relation to said actuating mechanism, said drum being of step-like form to provide a plurality of surfaces adapted for selective engagement by said detent to determine the position of said member, and means for shifting said member, a safety stop lever operable to disengage said detent from said drum, and means arranged to cooperate with said detent when it is disengaged by means of said lever to move said member toward and stop it in its neutral position.
25. A lathe comprising, in combination, a bed, rotatable work supporting means, a carriage slidable longitudinally of the bed, a cross slide movable transversely of said carriage, a member mounted in said carriage for limited movement longitudinally thereof, actuating means for said carriage connected to said member, actuating means for said cross slide including a slide movable longitudinally in said carriage, means for actuating said slide, a cam follower movable by said slide transversely of said carriage and operatively connected to said cross slide to move the same, said slide being arranged to provide a dwell for said cam follower, a wedge mounted in said carriage operable in one position to prevent transverse displacement of said slide, a lever mounted in said carriage and connected to said member and to said wedge and operable by said member when the return movement thereof is initiated to move said wedge to its inoperative position, said member and said carriage having engaging cam surfaces thereon arranged to cause transverse movement of said member toward said slide when the return movement of said block is initiated, said member acting in such movement to cause transverse movement of said follower to obtain a slight relieving movement of said cross slide.
26. A lathe comprising, in combination, a bed, rotatable work supporting means, a carriage slidable longitudinally on said bed, a cross slide mounted for transverse movement on said carriage, means for reciprocating said carriage including a member mounted in said

carriage for limited longitudinal movement relatively thereto, actuating means for said cross slide operable to advance said cross slide at the beginning of the carriage-advancing stroke and to retract said cross slide at the end of the carriage return movement and means connected to said member and cross slide and actuated by said member to cause a slight relieving movement of said cross slide at the beginning of the carriage return movement.

27. A lathe comprising, in combination, a bed, rotatable work supporting means, a carriage slidable longitudinally of said bed, a cross slide on said carriage, actuating mechanism for said carriage including a member mounted in said carriage for transmitting movement thereto, said member having a limited lost motion relatively to said carriage so that it has a small non-carriage-propelling movement whenever said actuating mechanism is reversed, means operable to cause displacement of said member in one transverse direction during such non-carriage-propelling movement in a carriage-advancing direction, and to return said member to its first transverse position during its non-carriage-propelling movement in a carriage-returning direction, and means operated by said member in its transverse movement to retract said slide while the carriage is stationary prior to its return movement, and to advance said slide while the carriage is stationary prior to its advancing movement.

28. A lathe comprising, in combination, a bed, rotatable work supporting means, a carriage slidable longitudinally of said bed, a cross slide on said carriage, actuating means for said cross slide including an element movable longitudinally in said carriage, a pin operatively connected to said cross slide and actuated by relative movement of said element to reciprocate said cross slide, said element being movable transversely from its normal position to permit said pin to be moved so as to retract said cross slide, a wedge movable longitudinally to and from an operative position wherein it maintains said element in its normal position, actuating means for said carriage including a member mounted in said carriage for transmitting movement thereto, said member having a limited non-carriage-propelling movement whenever said actuating means is reversed, means operated by said member in its non-carriage-propelling movement in a carriage retracting direction to move said wedge away from its operative position, said member also operating to move said pin and said element toward said wedge to retract the cross slide, said wedge-operating means being arranged to move said wedge to its operative position when said member is moved through its non-carriage propelling movement in an advancing direction.

29. A lathe having, in combination, a bed, rotatable working supporting means, a carriage mounted for longitudinal reciprocation on said bed, a cross slide transversely movable on said carriage, means for reciprocating said carriage and means for moving said cross slide comprising a member longitudinally slideable in said carriage and having a transverse slot therein having one end thereof open, a lever operatively connected to said cross slide to move the same when said lever is rocked, a pin on said lever adapted to engage said slot whereby to advance said cross slide when said member is moved in one direction, said member having one side thereof parallel to the path of movement of the member, said lever and pin being arranged so that said pin leaves said slot after a predetermined movement of said member and thereafter, during continued movement of the member, rides along said surface to hold said cross slide stationary, and means for moving said pin back into said slot when it becomes alined with the pin on the return movement of said member.
30. A lathe having, in combination, a bed, rotatable working supporting means, a carriage mounted for longitudinal reciprocation on said bed, a cross slide transversely movable on said carriage, means for reciprocating said carriage and means for moving said cross slide comprising a member longitudinally slideable in said carriage and having a transverse slot therein having one end thereof open, a lever operatively connected to said cross slide to move the same when said lever is rocked, a pin on said lever adapted to engage said slot whereby to advance said cross slide when said member is moved in one direction, said lever and pin being arranged so that said pin leaves said slot after a predetermined movement of said member, said member having a side surface arranged to engage said pin after it has left said slot to determine the transverse position of said slide, and means for moving said pin back into said slot when said slot becomes alined with said pin on the return movement of said member.
31. A lathe comprising, in combination, a bed, an upstanding headstock, a longitudinally extending rotatable headstock spindle mounted in said headstock, a movable tool support mounted on said bed, a power source, gearing for said headstock spindle comprising two differently speeded gear trains from said power source to said spindle, each of said gear trains embodying a pair of change gears and a clutch, one pair of said change gears being mounted on the outside of said headstock adjacent to each end of said spindle, and means for actuating said support from said spindle, said means including change gears and a clutch.
32. A lathe having, in combination, a bed, an upstanding headstock, a longitudinally extending headstock spindle rotatably mounted in said headstock, a movable tool support on said bed having actuating means driven from said spindle, a counter shaft mounted in said headstock parallel to said spindle and having splined ends projecting through the walls of said headstock, intermeshing gears on said spindle and countershaft, a first shaft mounted in said headstock parallel to said counter shaft and having a splined end projecting through one wall of said headstock adjacent to one splined end of said counter shaft, a pair of intermeshing change gears on the adjacent splined ends of said first shaft and said counter shaft, a second shaft mounted in said headstock parallel to said counter shaft and having a splined end projecting through the wall of the headstock adjacent to the other splined end of the counter shaft, intermeshing change gears on the projecting end of said second shaft and said counter shaft, and means for selectively actuating said first or second shafts.
33. A lathe comprising, in combination, a bed, an upstanding headstock having vertical walls, a longitudinally extending rotatable headstock spindle mounted in said headstock adjacent to the forward side thereof, a prime mover, a gear on said spindle, a counter shaft mounted in and projecting through opposite vertical walls of said headstock, a gear on said shaft engaging the gear on said spindle, a pair of shafts mounted in said headstock parallel to said counter shaft and projecting through said opposite vertical walls of the headstock, means for selectively connecting one of said pair of shafts to said prime mover, and change gears mounted on the projecting ends of said counter shaft and said pair of shafts to provide different operating speeds for said spindle.
34. A machine tool having a bed, a support movably mounted thereon, actuating means for said support, and controlling means for said actuating means including a movably mounted member having a plurality of operating positions, wherein said actuating means moves said support and another position wherein said actuating means is ineffective to move said support, means operating in timed relation to the movement of said actuating means to shift said member successively to its different positions to obtain an automatic cyclic movement of said support, a movable lever connected to said member and operable to move the same to any one of its positions, said lever being operable by movement in one direction to move said member from any one of its positions toward a predetermined one of its positions intermediate the end ones of said positions, and means to stop such movement of the member by said lever when said member has reached said predetermined position.

35. A machine tool having a bed, a support movably mounted thereon, actuating means for said support, and controlling means for said actuating means including a movably mounted member having a plurality of operating positions wherein said actuating means moves said support and another position wherein said actuating means is ineffective to move said support, and a movable lever connected to said member and operable by movement in one direction to shift said member from any one of its positions toward a predetermined one of its positions lying between two of its other positions, and means operable to stop such movement of said member by said lever when said member has reached said predetermined position. 70
36. A machine tool comprising a bed, a support movably mounted thereon, actuating means for said support, and controlling means for said actuating means including a movable element having a plurality of positions wherein said actuating means is effective upon said support and another position wherein said actuating means is ineffective, a lever operable by movement in one direction to move said member from any one of its positions toward another predetermined one of said positions lying between two of its other positions, and means operable to stop such movement of said member by said lever when said member had reached said predetermined position. 80
37. A lathe having a bed, a rotatable spindle, a support movably mounted on the bed, means for rotating said spindle and moving said support, a first pressure fluid actuated controlling means for controlling the rotation of the spindle by said actuating means, a valve for governing the passage of pressure fluid to said first controlling means, a second pressure fluid actuated means for controlling movement of said support by said actuating means, and a valve port connected to said second controlling means and governed by movement of said first controlling means to regulate the passage of pressure fluid through said port. 90
38. A lathe having a bed, a spindle, a support mounted on said bed, actuating means for rotating said spindle and moving said support, a pair of pressure fluid actuated devices, a first one for controlling rotation of said spindle by said actuating means and the other for controlling the movement of said support by said actuating means, and valve means operable to admit pressure fluid to said devices successively to said first pressure fluid actuated device and said other device. 100
39. A lathe comprising, in combination, a bed, a support movably mounted thereon, actuating means for the support, controlling means for said actuating means including a movable member having a plurality of positions each determining a different operating 110
- 40 condition for said actuating means, a series of abutments, a part connected to said member for movement relatively thereto and adapted to be engaged successively with said abutments to determine the various positions of said member, and means acting in timed relation to the movement of said actuating means and operable to shift said part from one abutment to another. 120
- In testimony whereof we have hereunto affixed our signatures.
- PEARL SUNDSTRAND,
Executrix of the Estate of Gustaf David Sundstrand, Deceased.
- JOHN F. BENNER. 130
